[57] ABSTRACT

A subfloor system for supporting machinery having hydraulically and electrically operated components. The system comprises a framework of horizontal beams some of which define trenches for hydraulic piping. The beams are raised on stools or pedestals to allow electric conduits to pass beneath. Anchor bolts are rigidly secured to the beams to anchor the machinery. At final installation, concrete is poured up to the level of the tops of the beams to embed the beams and the electrical conduits, but without filling the trenches so that the hydraulic piping remains accessible.

FIG. 5

FIG. 6

SUBFLOOR SYSTEM FOR GRINDING APPARATUS

BACKGROUND AND SUMMARY OF THE
INVENTION

The embodiment of the invention about to be described comprises a framework preferably made up of H beams which are raised on stools or pedestals and which have anchor bolts to anchor or tie down the machinery. Although other machinery may be used with the invention, the machinery described in this embodiment comprises a grinding machine and a carriage for moving a workpiece back and forth under the grinding wheel. Such machinery includes both electrical and hydraulic components.

The H beams, or some of them, define upwardly open trenches for the hydraulic piping serving hydraulically operated cylinders and motors. Electrical conduits pass below the raised H beams.

The entire subfloor system is encased in concrete up to the level of the tops of the H beams, embedding the electrical conduits in the concrete. The trenches for the hydraulic piping are not filled with concrete and therefore remain accessible. Removable plates may be employed to cover the tops of the trenches and lie substantially flush with the raised floor defined by the top surface of the concrete and the tops of the H beams.

The machinery is mounted on and anchored to the top surfaces of the H beams. Anchor bolts for tying down the machinery are welded or otherwise rigidly secured to the H beams.

This system allows the manufacturer of the machinery to erect the subframe consisting of the H beams and pedestals, to lay the hydraulic piping and the electrical conduit, to anchor the pieces of equipment to the H beams and then test all the machinery while in place to determine that it works properly. All this may be done in the manufacturer's plant before shipment to the customer and without pouring any concrete. After it is tested and adjusted so as to be in proper working order, the apparatus including the sub-framework, hydraulic piping, electrical conduit and machinery may be disassembled and shipped to the customer. In the customer's plant, the equipment may again be set up, but this time the concrete is poured to permanently embed the H beams and electrical conduit in the concrete.

In the past, manufacturers have not been able to set up machinery of this general type and fully test it before shipment. It was only possible to test the individual components separately. Also, in the past the concrete which was poured to form the floor and embed the electrical conduit had to be poured before the machinery was installed. Correction of mistakes in the electrical system could not be made without breaking up the concrete. Also, the poured concrete had to be formed with pockets in the surface located precisely where necessary to receive shear keys on the various pieces of machinery to prevent them from shifting during operation. It was difficult to locate these pockets with the high degree of accuracy required and therefore it became customary to form these pockets over-sized and then to grout the equipment in place after tryout.

According to the present invention, all of the adjustments and corrections may be made before the apparatus is shipped out of the manufacturer's plant, and the anchor bolts for tying down the machinery may be located exactly where needed so that when the apparatus

is set up again in the customer's plant the anchor bolts will be in exactly the right places.

In the drawings:

FIG. 1 is a semi-diagrammatic top plan view of apparatus embodying the present invention.

FIG. 2 is a sectional view taken on the line 2-2 in FIG. 1.

FIG. 3 is a sectional view taken on the line 3-3 in FIG. 1.

FIG. 4 is a sectional view taken on the line 4-4 in FIG. 1.

FIG. 5 is a sectional view taken on the line 5-5 in FIG. 1.

FIG. 6 is a fragmentary detail showing the connection between beams.

Referring now more particularly to the drawings, a subfloor system generally designated 10 is provided to support machinery which in this instance includes a grinding machine 12 having a grinding wheel G for removing metal from a workpiece W, and a reciprocable carriage C for supporting the workpiece and moving it back and forth under the grinding wheel. It will be understood, however, that the subfloor system of this invention may be used with other machinery than that here illustrated and described.

The subfloor system comprises essentially a framework including a plurality of elongated beams designated H1, H2, etc., which are supported on transverse stools or pedestals P1, P2, etc., in a raised horizontal position spaced above the permanent horizontal subfloor F. The beams are preferably H-shaped in cross section having horizontal top and bottom flanges and a vertical web. The pedestals are also preferably H-shaped in cross section although other configurations may be used.

While the arrangement of H beams may vary considerably depending upon the requirements of the particular machine installation, in this instance there is provided in FIG. 1 a pair of lateral H beams H1 and H2 disposed in laterally spaced parallel relation and associated generally with the grinding machine 12. Such H beams H1 and H2 are supported in horizontal position above the floor F by the pedestals P1-P4. To one side of the H beams H1 and H2 and parallel thereto are two additional H beams H3 and H4 which are disposed in laterally spaced parallel relation to one another and associated generally with the carriage C and related structure. Such H beams H3 and H4 are supported in horizontal position above the floor by the pedestals P5-P8. At one end of the parallel H beams H1-H4 are a pair of transversely extending H beams H5 and H6 which are associated generally with the mechanism for reciprocating the carriage C. Such H beams H5 and H6 are supported in horizontal, laterally spaced parallel relation above the floor by the pedestals P9-P12.

The H beams H1-H6 are thus supported with their top flanges in a substantially common horizontal plane. They may merely rest upon the pedestals or if desired they may be bolted or otherwise rigidly secured thereto, although preferably not permanently secured thereto during preliminary setup in the manufacturer's plant because of the necessity of disassembling the equipment for shipment.

Referring further to FIGS. 1 and 2, the grinding machine 12 comprises a base 20 which is rigidly secured to the H beams H1 and H2 by the anchor bolts 22. Such anchor bolts are elongated vertical members which are

disposed alongside the webs of the H beams and are welded or otherwise permanently secured to the top and bottom flanges of the H beams, projecting upward through openings in the top flanges of the H beams and through the base 20. Nuts are threaded on the upper ends of the bolts to rigidly secure the base upon the top flanges of the H beams.

The grinding machine has a saddle 24 which is reciprocable in ways 26 on the base transversely of the H beams H1 and H2. Such transverse reciprocation is effected by a hydraulic piston-cylinder assembly 28 which is mounted upon the base 20 and the rod of whose piston is connected to the saddle where indicated at 30. Any suitable means including hydraulic lines 29 and 31 may be employed to operate assembly 28.

The grinding machine has an elongated generally horizontal boom 32 carried by a mount 34 which is pivoted to the saddle 24 at 36. The grinding wheel G is rotatably mounted on the outer end of the boom and is driven by an electric motor 38 carried by the mount 34 by means of a belt 40 trained over pulleys 42 and 44 on the grinding wheel and on the motor. The boom 32 may be raised and lowered by a hydraulic piston-cylinder assembly 46 having a cylinder 48 pivoted to the saddle 24 at 50 and having a piston 52 reciprocable therein whose rod is pivoted to the mount 34 where indicated at 54.

Referring now to FIG. 3, there is shown a base 56 mounted on the H beams H1 and H2 and supporting a valve 58 and motor-pump assembly MP1 for use in the operation of the piston-cylinder assembly 46 to raise and lower the grinding wheel boom 32. Such base is rigidly secured to the top flanges of H beams H1 and H2 by the anchor bolts 22 like those previously described, such bolts being preferably welded in vertical position to the top and bottom flanges of the H beams and having nuts threaded on the upper ends as clearly shown in the drawings.

The valve 58 is operated by solenoids 55 and 57. It has a neutral position a in which hydraulic fluid is locked in both ends of the piston-cylinder assembly 46, a second position b for delivering hydraulic fluid to one end of the piston-cylinder assembly through one of the hydraulic lines 59, 61 and exhausting the other to raise the boom, and a third position c for reversing the hydraulic fluid lines to lower the boom. Valve 58 assumes its neutral position a when neither solenoid is energized, its position b when solenoid 55 is energized and its position c when solenoid 57 is energized.

Referring to FIG. 1, the base 60 spans the H beams H1 and H2 and is rigidly secured thereto by the anchor bolts 22 of the same construction as those previously described. The base 60 is provided to accommodate an operator's station which is only diagrammatically shown and includes an instrument panel 62 more fully described hereinafter. The operator at his station near the grinding machine is in a position to see the grinding operation and control the various functions.

Referring again to FIGS. 1 and 2, elongated rails 70 of I-beam construction are mounted upright upon the top flanges of H beams H3 and H4. The rails 70 are rigidly secured to the top flanges of the H beams by rail clips 72 which clamp over the tops of the bottom flanges of the rails and are secured in clamped position by the nut and bolt assemblies 74. The carriage C has wheels 76 which support the carriage on rails 70 for re-

ciprocation. The carriage is reciprocated by a reversible hydraulic motor 78 having an output drum 80 on which is wound a flexible linear member 82 one end of which is attached to one end of the carriage at 84. The other end of the flexible linear member 82 wraps around the idler drum 86 and is connected to the opposite end of the carriage at 88. The idler drum 86 is mounted for rotation on a base plate 90 at one end of rails 70 which is secured upon the top flanges of the H beams H3 and H4 by the anchor bolts 22. The hydraulic motor 78 is mounted on the base plate 92 secured by anchor bolts 22 upon the top flanges of H beams H5 and H6 at the opposite end of the rails 70.

A base plate 94 is mounted upon the top flanges of H beams H5, H6 by anchor bolts 22 and supports the motor pump assembly MP2 and valve 96 for operating the hydraulic motor 78. The valve 96 is operated by solenoids 95 and 97. It has a neutral position a in which hydraulic fluid is locked to prevent operation of the motor 78 in either direction, a second position b for delivering hydraulic fluid to the motor 78 through one line 98 while exhausting the other line 99 to rotate the drum 80 in one direction and a third position c for reversing the hydraulic fluid lines to rotate the drum 80 in the opposite direction. Valve 96 assumes its neutral position when neither solenoid is energized, its position b when solenoid 95 is energized and its position c when solenoid 97 is energized.

Trenches are provided between certain of the H beams. Thus there is a trench T1 between the H beams H1 and H2. The sides of the trench are defined by the H beams H1 and H2. The ends of the trench T1 are defined by the transverse H beams H7 and H8 which extend between and are secured to the H beams H1 and H2 in a manner more fully described hereinafter. H beams H7 and H8 are of the same configuration as H beams H1-H6 although shorter in length. The bottom of the trench T1 is defined by a plate 100 which extends between the bottom flanges of the H beams H1 and H2 and is rigidly secured thereto as by welding. Plate 100 extends from one transverse H beam H7 to the other H8 preferably also being welded or otherwise permanently secured to the bottom flanges of the transverse H beams. The trench T1, like the other trench to be described hereinafter, is open at the top but is normally preferably closed, at least between the base plate 20 and the base plate 56, by a removable cover plate 102 supported on elongated supporting strips 104 which are permanently secured as by welding to the undersurfaces of the top flanges of the H beams H1 and H2 and extend toward each other as illustrated in FIG. 2. Plate 102 is substantially flush with the top surfaces of the top flanges of the H beams to provide a continuous floor. Thus the trench T1 is accessible by removing the cover plate 102. As seen clearly in FIGS. 1, 2 and 3, the hydraulic pipes 59 and 61 are disposed in the trench T1, extending up through base plate 20 to the cylinder assembly 46 and up through the base plate 56 to the valve 58. Hydraulic pipes 29 and 31 from cylinder 28 also are disposed in trench T1. Thus the hydraulic piping is readily accessible.

Referring to FIGS. 1 and 5, a trench T2 is shown between the H beams H5 and H6. The trench T2 is bounded on the sides by the H beams H5 and H6 and on the ends by the transverse H beams H9 and H10 which are secured to the H beams H5 and H6 in a manner more clearly described hereinafter. H beams H9

and H10 are the same in configuration as those previously described although shorter in length. The trench T2 is closed at the bottom by a plate 110 extending between and rigidly secured as by welding to the bottom flanges of the H beams H5 and H6. The plate 110 extends from one transverse H beam H9 to the other H10 and is preferably also rigidly secured as by welding to the bottom flanges of such transverse beams. The trench T2 is open at the top, although normally closed by a cover plate 112 extending between the base plates 92 and 94 and supported along its side edges by elongated supporting strips 114 secured as by welding to the bottom surfaces of the top flanges H5 and H6 and projecting toward one another. Cover plate 112 is substantially flush with the top surfaces of the top flanges of the H beams.

The trench T2 is provided to receive the hydraulic pipes 98 and 99. The pipes at one end extend upwardly through base plate 92 to the motor 78 and at the opposite end extend upwardly through base plate 94 to the valve 96. Thus such hydraulic piping is readily accessible by merely removing the cover plate 112.

The instrument panel 62 has various switches as seen in FIG. 1. Switch S1 is for energizing solenoid 95, switch S2 is for energizing solenoid 97, switch S3 is for energizing solenoid 55, switch S4 is for energizing solenoid 57, switch S5 is for energizing motor-pump assembly MP1, switch S6 is for energizing motor-pump assembly MP2 and switch S7 is for energizing motor 38.

When installed in the customer's plant, the subfloor framework thus described is embedded in concrete 113 up to the top flanges of the H beams H1-H10 so that the top surfaces of such flanges are flush with the top surface of the concrete to provide a continuous horizontal floor. The top surfaces of the top flanges of all of the H beams, including the transverse H beams H7-H10 occupy a common horizontal plane. The concrete will not however flow into the trenches T1 and T2 because such trenches are closed at the bottom by the plates 100 and 110. Hence the hydraulic piping in the trenches is not embedded in concrete. However, the electrical conduit for the motor pump assemblies MP1 and MP2, the valves 58 and 96 and the grinding wheel motor 38 is embedded in the concrete. The wiring for the assembly MP1 is indicated at 120, for assembly MP2 at 122, for grinding wheel drive motor 38 at 124, for the solenoids 55 and 57 of valve 58 at 126 and 128 respectively, and for the solenoids 95 and 97 of valve 96 at 130 and 132 respectively. All of this wiring extends down from the associated assemblies beneath the level of the H beams H1 to H10 and then horizontally at such level to a position beneath the base plate 60 for the operator's station where such wiring then extends upward through the base plate 60 to the control panel 62.

The connection between the H beam H1 and the transverse beam H7 is shown in FIG. 6. It will be understood that the connections of all of the transverse beams H7, H8, H9 and H10 to the associated H beams H1, H2, H5 and H6 may be of the same description. As seen in FIG. 6, the H beam H7 is connected to the H beam H1 by angle members 140 and 142. One flange of each angle member is rigidly secured to the web of H beam H7 on opposite sides thereof by any suitable means such as welding. The other flanges of the two angle members are rigidly secured as by the nut and bolt assemblies 144 to the web of the H beam H1. The

connection shown in FIG. 6 is illustrative of one specific connection, although others may be provided.

When the manufacturer of the subfloor system and machinery above described wishes to test the equipment before shipping to a customer, the entire subfloor system minus the concrete, and with the machinery mounted thereon, may be set up in the manufacturer's plant. Anchor bolts at that time may be permanently installed as by welding to the H beams where necessary to mount the various parts of the machinery to the H beams in the proper places. The hydraulic piping and the electrical wiring may be hooked up and the machinery fully tested. After corrections and adjustments have been made, the machinery and the framework of the subfloor system may be disassembled and shipped. When subsequently installed in the customer's plant the subfloor framework is simply set up again and the machinery including all of its parts secured upon the framework to the anchor bolts previously installed and placed where needed in the manufacturer's plant. The trench bottom plates 100 and 110 are welded in place as are the cover plate supporting strips 104 and 114 at the customer's plant. The electrical conduit and hydraulic piping are installed and then the concrete is poured up to the level of the top surfaces of the H beams to complete the floor and embed the electrical conduit. However, as noted, the hydraulic piping is not embedded in concrete, being disposed in the trenches provided for that purpose and fully accessible by merely removing one of the covers 102 or 112.

When thus installed in the customer's plant, the top surfaces of the H beams are exposed, although substantially in the plane of the concrete, so that the various pieces of equipment tied down by the anchor bolts 22 may if desired be removed by merely removing the nuts threaded on the anchor bolts.

What I claim as my invention is:

1. A subfloor system for machinery having hydraulically and electrically operated components, comprising a plurality of beams, pedestals mounted on a subflooring and supporting said beams in substantially horizontal position spaced above the subflooring, a panel extending between selected ones of said beams and cooperating therewith to define an upwardly open trench, a cast material such as concrete encasing said pedestals and beams up to substantially the top surfaces of said beams but not filling said trench, the top surfaces of said cast material and beams providing a floor, means for mounting the machinery on the top surfaces of said beams, electrical wiring for the machinery embedded in said cast material, and hydraulic piping for the machinery disposed in said trench.

2. The subfloor system defined in claim 1, wherein said trench is closed by a removable cover extending between the top surfaces of said selected beams.

3. The subfloor system defined in claim 1, wherein said electrical wiring is disposed between or beneath said beams.

4. The subfloor system defined in claim 2, wherein said beams are H-shaped in cross section having substantially horizontal top and bottom flanges, said panel being carried by the bottom flanges of said selected beams and said cover being carried by the top flanges thereof.

5. The subfloor system defined in claim 4, wherein said top flanges of said selected beams have supporting elements for said cover.

6. The subfloor system defined in claim 1, wherein said means for mounting the components of the machinery comprises anchor bolts secured to said beams.

7. The subfloor system defined in claim 1, wherein said beams are H-shaped in cross section having substantially horizontal top and bottom flanges, said selected beams being arranged in laterally spaced parallel relation, said panel being secured to the bottom flanges of said selected beams, the top flanges of said selected beams having supporting elements secured thereto and projecting toward one another, and a removable cover extending over said trench and resting upon said supporting elements.

8. The subfloor system defined in claim 7, wherein said electrical wiring is disposed between or beneath said beams.

9. The subfloor system defined in claim 8, wherein said means for mounting the components of the machinery comprises anchor bolts rigidly secured to and projecting upwardly from said beams.

10. The subfloor system defined in claim 9, including in combination machinery components including an operator's control station, and electrical controls at said control station for said electrical wiring.

11. A subfloor system for machinery having fluid operated and electrically operated components, comprising a plurality of beams mounted over a subfloor in spaced substantially horizontal relation, an upwardly open trench defined between selected ones of said beams, a cast material such as concrete encasing said beams up to substantially the top surfaces of said beams but not filling said trench, the top surfaces of said cast material and beams providing a floor, means for mounting the machinery on the top surfaces of said beams, electrical wiring for the machinery embedded in said cast material, and fluid piping for the machinery disposed in said trench.

12. A subfloor system for machinery having electrically operated components, comprising a plurality of beams mounted over a subfloor in spaced substantially horizontal relation, a cast material such as concrete encasing said beams up to substantially the top surfaces of said beams, the top surfaces of said cast material and beams providing a floor, means for mounting the machinery on the top surfaces of said beams, and electrical wiring for the machinery embedded in said cast material.
